HARNESS CORD CONNECTOR FOR LOOMS

William A. Blanchard, Millbury, Mass., assignor
to Crompton & Knowles Loom Works, Worcester, Mass., a corporation of Massachusetts

Application November 26, 1948, Serial No. 62,211

6 Claims. (Cl. 139—82)

1

This invention relates to improvements in harness mechanism for looms and it is the general object of the invention to provide a harness cord connector which can be readily connected to and disconnected from a harness frame actuator.

In wide looms, such as narrow ware and paper makers felt, it is necessary to support the harness frames at several points along their length to prevent sagging. In the past these supports have been in the form of cords attached to solid connectors which surround an actuator, such as a rod operated by the shedding mechanism of the loom. These connectors are distributed along the rod but have been so made in the past that if one of them requires replacement it is necessary to remove several other connectors from the rod should the defective connector be near the center of the loom.

It is an important object of the present invention to provide a harness cord connector more particularly adaptable for use on wide looms having two parts slideable relatively to each other so that they will embrace the actuator by relative movements in two directions, thereby permitting attachment of the connector to the actuator without removing other connectors therefrom.

It is a more particular object of the invention to provide a harness cord connector having a body formed with a harness actuator receiving slot opening in one direction and a plug having a slot opening in a direction at right angles to the first slot and fitted into the body. The actuator is held within the slots by a set screw or the like which fastens the parts together and to the actuator. The plug member may be held against lateral displacement with respect to the body member of the connector by the set screw.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a front elevation of part of a wide loom having the invention applied thereto.

Fig. 2 is an enlarged front elevation of one of the connectors and associated parts.

Fig. 3 is a vertical section on line 3—3, Fig. 2.

Fig. 4 is a side elevation of the plug, and

Fig. 5 is a perspective view showing the manner of assembling the connector on the harness rod actuator.

Referring particularly to Fig. 1, the loom frame 10 supports a shedding mechanism comprising harness jacks 11, one of which is shown in Fig. 1.

2

These harness jacks are controlled by any approved form of mechanism, such as a dobby or Knowles head, and rock about their pivot 12. Extending lengthwise of the loom are long harness actuator rods one of which is shown at 13 connected by an eye 14 to jack 11. The arch 15 of the loom supports a plurality of harness sheaves 16 over which are trained harness cords 17. The latter are connected to the harness frame 18 at a plurality of points along the length thereof, such as 19, 20 and 21, to prevent sagging of the frame and resultant deformation of the warp sheds. In the past it has been customary to connect the harness cord 17 to the actuator rod 13 by means of connectors which slide along the rod but are not readily removable therefrom.

As a result of this prior practice breakage of a connector has required stoppage of loom operation long enough to permit some of the connectors to be slid off the rod and new connectors slid on to the rod.

The matter thus far described is common in any wide loom wherein the harness frames must be supported at several points.

25 In carrying the present invention into effect each harness cord 17 is associated with a connector designated generally at 25. One of these connectors is illustrated in detail in Figs. 2 to 5 where it will be seen that the connector comprises 30 a body member 26 having upwardly extending integral spaced preferably parallel walls 27 and 28 which define between them a slot 29 to receive the harness actuator rod 13. The walls have extending therethrough transversely of slot 29 35 aligned holes 30 which are preferably of circular form as shown in Fig. 2. Extending laterally from the body 26 to the right thereof as viewed in Fig. 2 are other walls 31 and 32 across which extends a stud 33 to receive a head 34 of the harness connector 17. The latter may if desired be 40 made of airplane cable, although the invention is not limited to harness cords made of this material.

A plug member 35 of generally cylindrical form 45 has a wall 36 formed integrally with laterally extending upper and lower lugs or walls 37 and 38, respectively, which define between them a slot 39 to receive rod 13. The lower lug 38 is provided with a hole 40 through which extends the upper 50 end of a set screw 41 threaded into a tapped hole 42 in the body member 26. The screw 41 enters slot 29 intermediate the walls 27 and 28 under the plug member.

The manner of assembling the connector to 55 the harness actuator rod 13 is indicated in Fig. 5.

The body 26 will first be lifted with respect to the connector rod 13 so that the latter will enter the slot 29, after which the plug member will be inserted into the holes 30 in such manner that the actuator rod 13 enters slot 39. After the two members of the connector are thus assembled the set screw 41 is threaded in the body 29 through the hole 40 until it engages the rod 13 as shown for instance in Fig. 2. By setting the screw 41 up tightly it will establish firm holding engagement between the body 26 and the rod 13 and will also by entry into the hole 40 prevent lateral displacement of the plug member. The set screw 41 forces the upper part of rod 13 against the under side of the top plug 37 and in turn forces the latter upwardly against the upper parts of the walls 27 and 28.

If breakage of any part of the connector 25 should develop during loom operation the connector can be removed from the rod 13 by a process the reverse of that followed in applying it to the rod. The set screw 41 can be backed off sufficiently to permit lateral removal of the plug member in a horizontal direction, after which the body member 26 will be moved downwardly. It will be seen that this operation can be performed without disturbing any of the other connectors which may be mounted on the actuator rod 13.

From the foregoing it will be seen that the invention sets forth a simple harness cord connector which can be readily attached to and removed from a harness actuator rod without disturbing other connectors which may be on the rod. The connector comprises body and plug members having rod receiving slots which extend transversely of each other, the slots as shown for instance in Fig. 3 being at right angles. When the two members are in operating position the rod is confined between the intersecting slots 29 and 39, and tightening of the set screw 41 will clamp or fasten the connector to the actuator rod. While the lateral walls 31 and 32 have been shown for attachment of the rod head 34 to the connector body 26 the invention is not necessarily limited to these lateral walls. Also, the positioning hole 41 in the plug member prevents accidental lateral displacement of the plug member and enables the set screw to have direct engagement with the rod 13 for the purpose of securing the connector to the rod.

Having thus described the invention it will be seen that changes and modifications of the foregoing specific disclosure may be made without departing from the spirit and scope of the invention.

What is claimed as new is:

1. In a harness cord connector for a loom having a harness actuator rod, a body member, a plug member extending transversely thereof, said members each formed with an open slot to receive said rod, the slots extending transversely of each other, and means on the body member to prevent relative transverse motion of the mem-

bers and secure the body and members to the rod.

2. In a harness cord connector for a loom having a harness actuator rod, a body formed with spaced walls defining a slot to receive said rod, a plug extending through said spaced walls and having spaced lugs defining a slot transverse of the first slot to receive the rod, and means on the body extending through one of said lugs for engagement with the rod to fasten the rod, plug and body together and prevent movement of the plug transversely of said walls.

3. In a harness cord connector for a loom having a harness actuator rod, a body member formed with spaced walls defining an open slot to receive the rod, a plug member extending transversely through said walls and having an open rod receiving slot therein extending across the first slot, and means supported by the body member extending through part of the plug member for engagement with said rod to fasten the body member to the rod and also prevent movement of the plug member transversely of said walls.

25 4. In a harness cord connector for a loom having a harness actuator rod, two rod engaging members each formed with an open slot to receive said rod, one slot capable of receiving the rod by movement relatively thereto in a given direction transverse of the rod and the other slot thereafter capable of receiving the rod by movement relative to the first member in a direction transverse of the rod and said given direction, and means on one member extending through the other member for engagement with the rod to hold both members in fixed position on said rod.

5. In a harness cord connector for a loom having a harness actuator rod, two rod engaging 40 members each formed with an open slot to receive said rod, one slot capable of receiving the rod by movement relatively thereto in a given direction transverse of the rod and the other slot thereafter capable of receiving the rod by movement relative to the first member in a direction transverse of the rod and said given direction, and a set screw tapped into one member entering said one slot and extending through part of the other member for engagement with the rod to hold both members fixed to the rod.

6. A body member for a harness cord connector provided with a plug member to engage a harness actuator rod, said body having parallel spaced walls defining a slot between them for reception of the rod, said walls having aligned holes therethrough transverse of said slot to receive said plug, said body having a screw threaded hole therein substantially parallel to and intermediate said walls to receive a set screw for engagement with the plug.
